UNITED STATES PATENT OFFICE.

CARL WILER, OF CHICAGO, ILLINOIS, ASSIGNOR, BY MESNE ASSIGNMENTS, TO
GENERAL ELECTRIC COMPANY, A CORPORATION OF NEW YORK.

INTERLOCKING DEVICE FOR REMOTE-CONTROL SWITCHES.

1,024,238.

Specification of Letters Patent. Patented Apr. 23, 1912.

Application filed October 18, 1908. Serial No. 455,334.

To all whom it may concern:

Be it known that I, CARL WILER, citizen of the United States, residing at Chicago, in the county of Cook and State of Illinois, have invented a certain new and useful Improvement in Interlocking Devices for Remote-Control Switches, of which the following is a full, clear, concise, and exact description.

10 My invention relates to an interlocking device for remote-control switches, and its object is to provide means that will prevent the closure of more than one of a plurality of associated switches at the same time.

15 As is well known, it is customary to provide remote-control switches for controlling from a distance the operation of electrically operated main switches in power plants. Such remote-control switches are 20 mounted on a board located at a distance from the main switches, and are arranged to operate the main switches by controlling a local circuit in which the operating mechanism for the main switches is located. The 25 main switches are frequently so interrelated that it is desirable that only one be closed at a time.

My invention is designed to control the closure of the remote-control switches and 30 thereby to control the closure of the main switches.

My invention contemplates providing the associated control switches with an interlocking device arranged so that it is not possible to operate more than one of the control switches at a time. Such interlocking device consists of a plate mounted to reciprocate between the shafts of the control switches, and adapted to be operated by said 40 shafts, so that in the operated position of one shaft, the shafts of the other switches are locked, and remain locked until the shaft of the previously operated switch is first moved to the open position and then re- 45 turned to its off position.

My invention may be more readily understood by reference to the accompanying drawings, in which—

Figures 1 to 8 inclusive show my invention as embodied in a well known type of rotary control switch, and Figs. 9 and 10 show the invention as embodied in a reciprocatory type of control switch. Fig. 1 is a plan view, partly in section, of a pair of

55 rotary switches provided with the interlocking device of my invention; Fig. 2 is a side elevation thereof, partly in section; Fig. 3 is a plan view of the interlocking plate with the casing thereof in section, and showing the position of the plate when one 60 of the switches is closed; Fig. 4 is a detail plan view, showing the manner of returning the interlocking plate to its normal position when a switch is moved from the closed to the open position; Fig. 5 is a detail plan 65 view of one end of the casing of the plate; Fig. 6 is a side elevation of the collar which is carried by the rotary shaft and which operates with the interlocking plate; Fig. 7 is a similar elevation taken at right angles 70 to the view shown in Fig. 6; Fig. 8 is a bottom plan view of said collar; Fig. 9 is an end elevation partly in section of a reciprocatory type of control switch provided with my invention; Fig. 10 is a plan view 75 of the apparatus shown in Fig. 9, with the casing which incloses the interlocking plate partly in section.

Similar letters of reference designate similar parts wherever shown.

Referring first to Figs. 1 to 8 inclusive, 1 is a bench-board upon which are mounted two rotary control switches of a well known type, the drum inclosing cases thereof being designated by the reference numerals 85 2, 2, and the rotary shafts by the numerals 3, 3, respectively. Each shaft is adapted to be rotated in the usual manner by a handle 4. Lying upon the top of the board 1, and extending from one shaft 3 to the other, is 90 a reciprocatory interlocking plate 6, which is inclosed by a casing or cover 7. The top of the central portion of the plate 6 may be hollowed out as at 8 to receive a bent spring 9 which is secured to said plate, the free 95 ends of said spring frictionally engaging with the inner face of the casing 7, thereby preventing said plate from accidentally working out of operative position. Each 100 end of the plate 6 is in the form of a loop 10 which incloses the corresponding rotary shaft. Each shaft 3 is provided with a fixed collar 11 having radially projecting lugs 12, 13 arranged at approximately right angles to each other. Pivoted upon the lug 105 12 is a dog 14 held under the tension of a flat spring 15. Said dog is adapted when the rotary shaft 3 is rotated toward the

closed position of the switch, to engage with a notched plate 16 carried by the plate 6, and thereby upon the rotation of the shaft to move the plate in a longitudinal direction 5 toward the other shaft 3. In the off position of a switch the collar 11 is in such position that the lug 13 thereof extends toward the shaft of the opposite switch, as shown in Fig. 1. Assuming that, from the positions 10 shown in Fig. 1, the left hand switch be rotated clockwise to the closed position, the dog 14 will cause the plate 6 to slide to the right, and the lug 13 upon the collar of the right hand switch will engage a longitudinally extending recess 17, in the corresponding end of the plate 6. The right hand switch is thus locked against rotation until the plate 6 is returned to the position shown 15 in Fig. 1. This, as will appear, cannot be done until the left hand switch is first moved to the open position. If from the position shown in Fig. 3, the left hand switch be rotated counter-clockwise to the intermediate or off position merely, the plate 6 remains 20 in the position to which it has been shifted, and hence the right hand switch cannot be operated. If, however, the left hand switch be further rotated counter-clockwise toward the open position, the lug 25 30 will engage the inner cam surface of the loop 10 and draw the plate 6 to the left, returning the same to the position shown in Fig. 1. For the purpose of providing the lug 12 with a surface adapted to engage 35 with the cam surface of the loop 10, I preferably form said lug with a flange 18 on its bottom face, as shown most clearly in Figs. 6, 7 and 8. The two ends of the plate 6 are preferably symmetrical, and the operation 40 of the right hand switch, whereby the other switch is locked, is similar to the operation already described. Fig. 4 shows in full lines the position the parts have assumed at the right hand switch, when said switch has 45 been first moved to the closed position, and then returned only to the intermediate or off position. The dotted lines of Fig. 4 show the switch moved to the open position and the consequent movement of the plate 50 6. It will be observed that the cam surface of the loop 10 is such that the flange 18 of the lug 12 engages therewith only during the rotation of the switch from the open to the off position, and that by moving one 55 switch from the off to the closed position the reciprocating plate 6 is moved into locking engagement with the shaft of the other switch, and remains in such position until the operated switch is moved to the open 60 position, said latter movement returning the plate to its initial non-locking position.

Figs. 9 and 10 show a well known type of reciprocating switch in which the movable member 20 is pivoted at 21 and is normally 65 spring-pressed into the intermediate or off

position shown in Fig. 9. The shank 22 of the movable member is provided with a handle 23. By grasping the handle 23 and moving the same to the right or to the left in Fig. 9, which corresponds to movement up or down in Fig. 10, the movable member is moved into the closed or open position, respectively, of the switch. Upon releasing the handle the spring 24 returns the same to the off position shown in Fig. 9. Said switches are likewise mounted on a bench-board 1. The interlocking plate 25 is adapted to reciprocate in guideways formed in the easing 26, which is secured upon the outer face of the board 1. Said easing is provided with transverse slots 27, one at each end, to permit the reciprocation of the shank 22. At each end thereof the plate 25 is provided with an irregular loop 29, through which the shank 22 extends. Adjacent to the connecting body portion of the plate 25 each loop extends inwardly to form a groove or recess 30 adapted to receive the shank 22 of the movable switch member. When either shank 22 is completely in the groove 30, such shank is locked against reciprocation, as is, for example, the shank at the right end of Fig. 10.

As shown in Fig. 10, one side of each loop 29 is provided with a beveled cam surface 31. When the shank of the switch which is not locked against operation, as, for example, the shank of the switch at the left in Fig. 10, is pressed down to move the switch into the open position, such shank rides against the cam surface 31 and moves the plate 25 in a position to release the other switch. When both switches have been moved to the open position and have returned to the off position, each shank 22 lies at the mouth of the corresponding groove 30, and either switch may be closed. In closing a switch, as by moving the shank 22 upward, said shank rides over the curved cam surface 32, moving the plate 25 so that the shank 22 of the other switch is brought into the recess 30, as shown in the right in Fig. 10. The latter switch is thus locked and remains locked until released by the movement of the other switch to the open position. It is obvious, therefore, that in both embodiments of my invention shown in the drawings, one only of a plurality of associated switches can be operated at a time to close a main switch, the remaining switch or switches being locked against closure until the previously operated switch has been moved to the open position.

While I have shown and described the interlocking plate as having the opposite ends similar, so that the operation of either switch will control the operation of the other, it is obvious that the ends of the plate may be varied in shape to adapt it to other conditions which may arise in practice

without departing from the spirit of my invention.

I claim:

1. The combination with a plurality of switches each having two operative positions and an inoperative position between the operative positions, of a movable locking member coöperating with said switches, means whereby said member is moved to locking and unlocking positions respectively with reference to one switch when the other switch is moved to either operative position but is unmoved when the switch is moved to the inoperative position.
2. In a rotary switch, the combination with the shank thereof, of a collar fixed to said shank, a slidable plate mounted in an operative relation to said collar, a dog carried by said collar and means provided for said plate adapted to coöperate with said dog, whereby the movement of said switch to a closed position will operate said plate in one direction and the subsequent movement of said switch to the open position will return the plate to its initial position; and a second switch mounted in position to be locked or unlocked in its off position by the one or the other positions, respectively, of said plate.
3. In a rotary switch, the combination with the shank thereof, of a collar fixed to said shank, a spring-pressed dog carried by said collar, a slidable plate mounted in position to be engaged and operated by said dog upon the rotation of said switch to the closed position, said plate being provided with a cam surface coöperating with said collar to return said plate to its normal position upon the rotation of said switch to the open position, and a second switch mounted in position to be locked or unlocked in its off position.

tion by the forward or backward movement, respectively, of said plate.

4. In an associated group of rotary switches, the combination with the operating shanks of said switches, of a collar carried by each shank, a dog pivotally mounted upon the collar, a locking lug projecting radially from the collar, and a slidable plate interconnecting said switches, said plate being provided at each switch with a loop inclosing the shank thereof, said loops being each provided with a recess in line with said shanks, each of said recesses being adapted to receive, in the off position of a switch, the locking lug of the corresponding collar, and each of said loops being provided with a surface adapted to be engaged by the dog, upon the closure of a switch, to move the plate into locking engagement with the locking lugs of the remaining switches, and also with a cam surface adapted to be engaged by said collar, upon the subsequent movement of the operated switch to the open position, to release said plate from engagement with said locking lugs.

5. The combination with a plurality of switches, of an interlocking member movable between said switches, an operating dog movable as each switch is actuated to bring the interlocking member into and out of engagement with another switch, and a locking dog movable with each switch into a position to be engaged by and disengaged from the interlocking member.

In witness whereof, I, hereunto subscribe my name this 16th day of October A. D., 1908.

CARL WILER.
